UNITED STATES PATENT OFFICE

EMIL MILNER AND FRANK WALTER, OF PHILADELPHIA, PENNSYLVANIA

NEEDLE SELECTING DEVICE FOR KNITTING MACHINES AND THE LIKE

Application filed March 26, 1931. Serial No. 525,448.

Our present invention relates to needle selecting devices for knitting machines and the like and more particularly to the controlling mechanisms of such devices.

5 While it is intended primarily that our invention be used for selecting knitting needles of the spring type, as distinguished from those of the latch type, it is to be understood that by minor changes and rearrangements in the driving mechanism, our invention may also be applied for the selection of knitting needles of the latter type.

10 Before describing our invention in detail, it may be desirable to briefly point out some of the disadvantages accompanying the use of similar devices in this particular branch of the knitting art.

15 Heretofore, needle selecting devices, otherwise known as main pattern wheels, were separate and individual members, only one of which could be used at a time on a particular knitting machine. As a result, each time that it was desired to change the pattern, it was necessary to stop the knitting machine entirely and disengage the pattern wheel already in operation in said machine and replace it with the needle selecting member of the new pattern. Obviously, such a procedure consumed considerable time and energy which increased the expense of the finished product manufactured by knitting machines employing such needle selecting members.

20 It is therefore the main object of our invention to overcome the disadvantages of prior similar devices by providing means for automatically withdrawing a particular needle selecting member from its operative position, said member embodying a particular design, and replacing such member with another needle selecting member embodying a different pattern or design.

25 It is another object of our invention to effect the foregoing purpose without the need of discontinuing the operation of the knitting machine and without any human intervention whatsoever, thus lowering the final cost of the knitted products made by 30 the machines in which the device may, in ac-

cordance with the principles of our invention, be included.

These and other objects, such as ease and inexpensiveness of fabrication, ready assembly and simple operation, are attained by the 55 novel construction, combination and arrangement of elements hereinafter described and illustrated in the associated drawings, constituting a material component of this disclosure and in which:—

Fig. 1 is a top plan view of the preferred embodiment of our invention assembled for operation;

Fig. 2 is a top plan view of the preferred drive used with our invention;

Fig. 3 is a side elevational view of the same;

Fig. 4 is a front edge view thereof;

Fig. 5 is a longitudinal sectional view taken on line 5—5 of Fig. 3;

Fig. 6 is a fragmentary side elevational view of one of the cam elements used in the aforesaid embodiment of our invention;

Fig. 7 is a rear edge view of the same;

Fig. 8 is a side elevational view of the 75 assembled pattern wheel shifting mechanism used in our invention;

Fig. 9 is a top plan view of the cam element embodied in the aforesaid pattern wheel shifting mechanism;

Fig. 10 is a top plan view of a pattern 80 wheel selecting device made in accordance with our invention;

Fig. 11 is a front elevational view of the same;

Fig. 12 is a fragmentary transverse sectional view taken on line 12—12 of Fig. 11, the outer cover being partially broken away to show the inner construction;

Fig. 13 is a side elevational view, partly 90 broken away, of the device shown in Fig. 10;

Fig. 14 is a partial top plan, partial transverse sectional view illustrating the pivoted link connections associated with the pattern wheel shifting mechanisms above referred to;

Fig. 15 is a detail top plan view of the 95 needle selecting members or main variable pattern wheels; and

Fig. 16 is a longitudinal sectional view taken on line 16—16 of Fig. 10.

Referring now more in detail to the drawings:

5 We shall first describe the preferred driving mechanism which we intend to use with our invention, although it is to be understood, particularly by those skilled in the art to which the present invention relates, 10 that by making minor changes, any suitable driving mechanism may be employed.

In the preferred driving mechanism shown in Figs. 1 to 9, inclusive, of the drawings, the numeral 10 Fig. 1 generally designates a flat platform which may be a permanent part of the knitting machine proper and secured on the platform, as by bolts 10', is a substantially L-shaped base 15, from the rear edge of which rises a standard 16 15 Fig. 2 of square cross section, having near the upper end thereof a stud 17 Fig. 3. Pivoted on said stud is a lever 18 having at the outer end thereof the bent portion 19 carrying a stud 20 on which is rotatably mounted a roller 21, this roller being adapted to contact with the inclined cam surface 22 of the cam element 22' fixedly attached to the side of the needle drum 23 carrying the needles N, the drum being part of the knitting machine proper, not shown herein since it is no part of the present invention. The opposite end of the lever 18 is pivotally connected by a pintle 24 to a pawl 25 extending upwardly to engage a ratchet wheel 26 Fig. 1, having the sleeve portion 26' revolvably mounted on a shaft 27 fixed in the upper end of a second standard 28 also of square cross section, by a lock nut 29, this second standard rising from one of the rear corners of the base 15.

45 Fixed to the upper end of the second standard 28 by the screw 30 is an extending arm 31, to the outer end of which is fixed one end of a tension spring 32 Fig. 3, the opposite end of which is fastened to a lug 33 formed on the lower rear edge of the pawl 25.

50 Mounted on the shaft 27 is a sprocket wheel 34 Fig. 5, this sprocket wheel being slightly spaced from the sleeve 26' and connected thereto by a pin 34', and formed on the outer face of the sprocket wheel 34 is a second ratchet wheel 35 engaged by a pawl 36 Fig. 3 pivotally mounted on a stud 37 55 carried by a supporting arm 38, having at its end a collar 39 Fig. 1 by which the same is fixed on the outer free end of the shaft 27, the same being held in place by a pair of set screws 40. Engaged in the supporting arm 38 just below the collar 39 and in a line with the shaft 27 is a screw 41 Fig. 4 to which is fixed one end of a tension spring 42, the other end of which engages a stud 43 extending outwardly from the pawl 36, 60 so that the same is normally held in positive

engagement with the second ratchet wheel 35.

70 Projecting outwardly from the top of the standard 16 is an arm 44 Fig. 2 having the downwardly extending portion 45 acting as a stop against which the lever 18 abuts at the top of its upward movement and adjacent the standard 16 is a third standard 46, cut away to form the seat 47 Fig. 4 upon which the lever 18 is normally retained by the action of the tension spring 32.

75 Engageable in the standard 28 is a threaded stud 48 Fig. 3 on which is pivoted a lever 49 carrying a stud 50 on its outer face to which is fixed one end of a tension spring 51, the other end being secured to the horizontal extending portion 52 Fig. 1 of the arm 44. The spring 51 normally maintains the lever 49 in its upper position against the projection 53 fixed in the standard 46 and the lever is limited in its downward movement by a flat spring 54 secured to the base 15 by bolts or rivets 55.

80 Formed on the outer end of the lever 49, at a right angle thereto, is a bar member 56 Fig. 4 tapered at one end to present the cam surfaces 56' and 56'', respectively, upper and lower. The other end of the lever 49 carries a stud 57 Fig. 5 to which is pivoted a plate lever 58 provided with a substantially central, elongated slot 59 adapted to accommodate the shaft 27, the lever being positioned intermediate the sleeve 26' of the ratchet wheel 26 and the sprocket wheel 34.

85 The upper end of the lever 58 carries a stud 60 on which rotates a cam roller 61 adapted to be engaged by cam links 62 Fig. 3 positioned at predetermined intervals for a purpose later to become apparent, along an endless chain 63 trained over the sprocket wheel 34.

90 The needle drum 23 carries a pair of spaced threaded studs 64 Fig. 8 and Fig. 9 engaging slots 65 formed in short vertical bars 66 connected by a yoke 67, there being a pair of spaced semitriangular members 68 extending outwardly from the yoke for a purpose later to be described.

95 One of the bars 66 is provided in one of its side edges with a notch 69 to receive the operative pointed end 70 of the stop 71, in order to maintain the bars 66 and their associated parts in their adjusted positions, as will later be seen.

100 The stop 71 is provided with horizontal, aligned slots 72 receptive of adjustable studs 73 mounted in the needle drum 23. The stop is constantly maintained in contact with the edge of the adjacent bar 66 by a tension spring 74, one end of which is fixed to a stud 75 carried by the stop and the other end of which is fixed to a stud 76 in the drum 23.

105 This completes the description of the pre-

ferred form of driving mechanism which it is desired to employ for operating the needle selecting devices made in accordance with the present invention, the operation of which may be briefly summarized as follows:

As the cam 22' Fig. 1 rotates with the drum 23, it will, during the course of its rotating, engage, along its rising cam surface 22, the roller 21 to rock the lever 18 which in action in turn, through the pawl 25 and ratchet wheel 26, rotates the sprocket wheel 34.

The sprocket wheel 34 is prevented from rotating in the direction opposite to that in which it is driven by the ratchet wheel 26, by the engagement of the pawl 36 with the second ratchet wheel 35.

As the sprocket wheel 34 rotates, one of the cam links 62 of the chain 63 will engage the roller 61 to raise the plate lever 58. This action rocks the lever 49 to place the bar member 56 in its lower position, shown by dotted and dash lines in Fig. 8 of the drawings. Then, as the drum 23 continues to rotate, the cam surface 56' of the member 56 engages the nearest lower corner edge of the yoke 67 to raise that element and its associated parts to actuate the needle selecting mechanism later to be described.

After the cam link 62 has passed the roller 61, the bar member will be returned, by the action of the spring 51, to its uppermost position, indicated by dotted lines in Fig. 8 of the drawings. With the member 56 in this position, the next rotation of the drum 23 will cause the yoke 67 to be engaged at the nearest upper corner by the lower cam surface 56'' of the member 56, thus lowering the yoke and its associated parts to again actuate the selecting mechanism, as will later be seen.

It is to be understood that there may be provided a plurality of cam members 22' and yokes 67, depending upon the number of times and at what intervals it is desired to operate the selecting mechanism to change the pattern.

As stated above, all of the foregoing merely constitutes the preferred driving mechanism to be employed with the needle selecting devices of our invention and it is not absolutely essential that this exact driving mechanism be used, inasmuch as any suitable driving mechanism adapted to receive its motion from any of the usual operative parts of the knitting machine proper, may be ably substituted.

We shall now describe the needle selecting devices made in accordance with the present invention and which are illustrated more in detail in Figs. 1 and 10 to 16, inclusive, of the drawings.

In these figures, the numeral 80 generally designates a substantially flat base fixed adjacent the base 15 on the platform 10, at the

rear edge of which is formed a boss 81 Fig. 13 in which is fixed, by means of the lock nut 82, a stationary vertical shaft 83. Formed on the rear surface of the boss 81 are channelled guides 84 in which slides a flat supporting bar 85 provided with a slot through which passes a set screw 87 carrying a washer 88 which abuts the bar 85, the screw being anchored in the boss 81, so that the bar may be adjusted in various positions.

Secured to the upper end of the bar 85 by a screw 89, is an L-shaped block 90 Fig. 1 having channelled guides 91, Fig. 13, and 92 on the upper and lower surface thereof, said guides being at right angles to the bar 85.

Slidable in the guides 91 and 92 are slide bars 93 and 94, upper and lower, respectively, carrying at the outer ends thereof collars 95 and 96 in which are rotatable the hubs 97 and 98 of the needle selecting members or pattern wheels 99 and 100, the backs of which contact each other and the outer peripheries of which are provided with the projections 101 and 102 Fig. 11 and the intermediate depressions 103 and 104, constituting the means of selecting the desired knitting needles, which means is more fully described in Patent No. 1,880,267, issued to Emil Milner, on October 4, 1932, entitled "Needle selecting mechanism for knitting machines and the like."

Passing through the hubs 97 and 98 is a rod 105 Fig. 16 having the central reduced portion 106 and the flattened key portions 107 and 108 at the outer ends thereof, said key portions being engageable in the key slots 109 and 110 formed by the cutaway edges of the contacting plates 111, 111a and 112 and 112a which are fixed by screws 113 and 114 Fig. 13 to caps 115 and 116, engageable over the hubs 97 and 98 and fastened thereto by set screws or any other similar fastening means.

Projecting outwardly from the outer faces of the slide bars 93 and 94 are studs 119 and 120 to which are pivotally engaged links 121 and 122, the opposite ends of which are rotatably mounted on studs 123 and 124, each being threadedly engaged in one of the arms 125 and 126 Fig. 14 of a pair of rocking levers 127 and 128 Fig. 11 rotatably mounted on the shaft 83, said levers being spaced apart by a spacer or collar 129.

The other arms 130 and 131 of the rocking levers 127 and 128 are enlarged at their outer ends and provided with the aligned slots 132 and 133 Fig. 14 in which are adjustably carried studs 134 and 135 threaded to receive lock nuts 136 Fig. 10. Carried by the studs 134 and 135 are lugs 138 and 139 Fig. 1 to which are fixed the ends 140 of tension springs 142, the opposite ends 144 of which are fixed to a vertical supporting rod 146 rising from the base 80.

Also formed on the base 80 is a bearing

147 Fig. 13 in which is journaled one end of a shaft 148, the upper end of which is journaled in the outer free end 149 of a supporting arm 150 having a collar 151 formed on the inner end thereof and which is fixed by a set screw or the like to the upper end of the shaft 83.

The lower end of the shaft 148 is provided with a circumferentially disposed track 153 Fig. 12 having a plurality, here shown as four, equi-distantly spaced stop depressions 154, formed therein, said track being engageable by a plunger 155, the outer end of which abuts an expansion spring 156, compressed by a thumb screw 157 threaded engaged in the outer end of the bearing 147.

The shaft 148 carries, just above the bearing 147, a wheel 158 having the semi-triangular projections 158, which are engaged by the members 68 of the yoke 67, as shown in Fig. 12 of the drawings.

Also fixed on the shaft 148 are a pair of oppositely disposed cams 160 and 161 Fig. 11, corresponding respectively to the rocking levers 127 and 128, said cams engaging studs 162 and 163 Fig. 14 formed on floating levers 164 and 165, the ends of which are pivotally connected to the shaft 148 and studs 134 and 135. The floating levers 164 and 165 are kept apart by means of the spacer 166 Fig. 11 also carried by the shaft 148.

Thus, it is to be seen that when the yoke 67 is moved upwardly, as previously described, by the bar member 56, into the path of the members 158' of the wheel 158, continued movement of the drum 23 causes the member 68 to engage the members 158' and thereby rotate the shaft 148. This causes the rotation of the cams 160 and 161, which, through engaging the studs 162 and 163 of the floating levers 164 and 165, causes the alternate actuation of the rocking levers 127 and 128. Because of the pivoted link connections 119 to 124, inclusive, between the rocking levers 127 and 128 and the sliding bars 93 and 94, movement of the rocking levers imparts a reciprocating motion to the sliding bars and because of the cams 160 and 161 being oppositely disposed, these reciprocating motions are opposite or alternated. It is therefore to be noted that in view of the alternating reciprocating movement of the slide bars 93 and 94 first the operative edge of the needle selecting member 99 is presented to the row of spring needles meant to be operated, and then, as this needle selecting member is withdrawn by the backward movement of the sliding bar 93, caused by the operation of the parts heretofore described, the operative edge of the needle selecting member 100 is presented to the spring needles meant to be operated for this particular design.

From the foregoing, it will be noted that a plurality of needle selecting members may be alternately moved into and out of operative positions and that such movements are attained automatically so that it is unnecessary to discontinue the operation of the knitting machine proper in order to stop the use of one design and commence with another and that in view of such entirely automatic operation, time and energy and thus expense is minimized with the obvious advantages to the ultimate consumer of the knitted articles made by the knitting machines equipped with the attachments of the present invention.

While the foregoing is descriptive of the preferred embodiments of our invention, it is to be clearly understood that we do not wish to be limited specifically to such embodiments, as obviously minor changes in the details of construction thereof may be made without the exercise of the inventive faculties or departing from the spirit and scope of the claims hereto appended.

Having thus described our invention, what we claim as new and desire to secure by Letters Patent is:

1. In a device of the character described, a pair of reciprocating needle selecting members mounted back to back on a single shaft and means to reciprocate said needle selecting members into and out of operative position.
2. In a device of the character described, a pair of reciprocating needle selecting members mounted back to back on a single shaft and means to alternately reciprocate said needle selecting members into and out of operative position.
3. In a device of the character described, a pair of reciprocating needle selecting members mounted back to back on a single shaft and means to reciprocate said needle selecting members into and out of operative positions, said means comprising cam means and connections intermediate said cam means and said reciprocating needle selecting members.
4. In a device of the character described, a pair of reciprocating needle selecting members mounted back to back on a single shaft and means to alternately reciprocate said reciprocating needle selecting members into and out of operative positions, said means comprising cam means and connections intermediate said cam means and said reciprocating needle selecting members.
5. In a device of the character described, a pair of needle selecting members mounted back to back on a single shaft, a cam corresponding to each of said needle selecting members and means intermediate said needle selecting members and said cams to transmit motion from the latter to the former.
6. In a device of the character described,

a pair of reciprocating needle selecting members mounted back to back on a single shaft, a cam corresponding to each of said reciprocating needle selecting members and means intermediate said reciprocating needle selecting members and said cams to transmit reciprocating motion from the latter to the former.

7. In a device of the character described, 10 a pair of needle selecting members mounted back to back on a single shaft, a cam corresponding to each of said needle selecting members and means intermediate said needle selecting members and said cams to alternately move said needle selecting members into and out of operative positions.

8. In a device of the character described, 20 a pair of reciprocating needle selecting members mounted back to back on a single shaft, a cam corresponding to each of said reciprocating needle selecting members and means intermediate said reciprocating needle selecting members and said cams to alternately reciprocate said reciprocating needle selecting members into and out of operative positions.

9. In a device of the character described, 30 a pair of needle selecting members mounted back to back on a single shaft, a cam corresponding to each of said needle selecting members and pivoted lever connections intermediate said needle selecting members and said cams.

10. In a device of the character described, 35 a pair of needle selecting members mounted back to back on a single shaft, a pair of oppositely disposed cams and pivoted lever connections intermediate said needle selecting members and said cams, whereby said needle selecting members are alternately reciprocated into and out of operative positions.

11. In a device of the character described, 45 a guide block, a pair of slide bars reciprocably mounted in said guide block, a needle selecting member carried by each of said slide bars, a pair of rocking levers having one arm of each pivotally connected to its corresponding slide bar, a pair of oppositely disposed cams corresponding to said rocking levers, floating levers intermediate said cams and said rocking levers and a stud on each of said floating levers engageable by said cams, whereby rotation of said cams 50 imparts opposite reciprocating motions to said needle selecting members.

12. In a device of the character described, 55 a pair of parallel slide bars, needle selecting members carried by said slide bars, the backs of said needle selecting members being in contact with each other and having enlarged central apertures, a rod having a reduced central diameter passing through the apertures of said needle selecting members and means to reciprocate said slide

bars, whereby said needle selecting members are alternately moved into and out of operative positions.

In testimony whereof, we have signed our names to this specification this 2nd day of 70 February, 1931.

EMIL MILNER.
FRANK WALTER.
